INVENTOR

BY J. M. Thomas

ATTORNEY

UNITED STATES PATENT OFFICE.

CHARLES H. ROBERTS, OF SALT LAKE CITY, UTAH.

WAVE AND CURRENT MOTOR.

1,300,194.

Specification of Letters Patent. Patented Apr. 8, 1919.

Application filed June 10, 1918. Serial No. 239,321.

To all whom it may concern:

Be it known that I, CHARLES H. ROBERTS, a citizen of the United States, residing at Salt Lake City, in the county of Salt Lake 5 and State of Utah, have invented certain new and useful Improvements in Wave and Current Motors, of which the following is a specification.

My invention relates to waves motors or power generation from flowing water, and has for its object to provide a machine to be placed on a beach or in a flowing stream and utilize the force of the flowing water when applied on a plurality of spaced apart 15 rectangular blades each of which is fastened on a chain belt mounted to present adjustable parallel leads of said belt.

These objects I accomplish with the machine illustrated in the accompanying drawings in which similar letters and numerals of reference indicate like parts throughout the several figures and as described in the specification forming a part of this application and pointed out in the appended claims.

In the drawings in which I have shown a substantial embodiment of my invention, Figure 1 is a side elevation of the machine. Fig. 2 is an end elevation of the same. Fig. 3 is a plan view of one end portion showing parts of the frame on which the machine is mounted.

The present invention is intended for use on an ocean beach whereby the force of the waves alone or the force of the waves and the undertow may both be used to develop power, or as will be obvious it may be used in a running stream and the gravity flow of the water applied to the lower lead of the belt to develop power thereby.

I mount the machine on a frame consisting of parallel stringers A, supported on posts B. On the inside of said posts B are secured the angle iron supports 1 which are spaced apart to form a vertical channel 45 therebetween and in which channel the end frames C are slidably mounted for vertically adjusting the chain belt to the pitch of the beach. Between each pair of said angle irons 1 is mounted one of the axles 4 of the lower sprocket wheels 2. To one of said angle iron supports 1 at each corner of the frame is pivoted one end of one of the upper sprocket wheel braces 3. The upper sprocket wheels 5 are secured on an axle 6 55 which is journaled in bearings 7 that are

fastened on said braces 3. A pair of endless chains 8 are operated over the said sprocket wheels 2 and 5, and are formed into a belt by the blades 9 which are fastened thereto at an angle relative to the run of the 60 said belt. The reaches of said chain belt are to be kept parallel and the space between the reaches is adjustable by raising or lowering the free ends of the said braces 3 which is accomplished by means of manually 65 operated ratchet pinions 10, the teeth of which engage the racks 11. The said pinions 10 and racks 11 are each mounted in a frame D which in turn is mounted on the cross piece 12 of the frame C. The said pinions 10 are rotated by the hand cranks 13, and the lower end of each of said racks 11 is connected with a U-shaped link piece 14 the legs of which are pivoted in the free 70 ends of said braces 3. A sprocket wheel 15 75 is also secured on said axle 6 and a chain 16 carried thereon carries or imparts the power developed to machinery not shown.

The operation of my machine is as follows:

When it is used on an ocean beach the leads of the chain belt are adjusted to the pitch of the beach by adjusting the vertical position of the said frames C relative to the angle irons 1 and fastening the said frames 85 C when so adjusted. The adjustment of the reaches of the said chain belt is to each other and as to the waves and depth of the undertow as made by raising or lowering the free 90 ends of the braces 3, which is done by rotating the pinions 10 and raising or lowering the racks 11 and by means of the said U-shaped pieces 14 adjusting the said braces 3 to the desired position for the run of the upper lead of the chain belt and blades 9 95 in order that the incoming waves may act on the blades 9 of the upper lead while the undertow acts on the blades 9 of the lower lead of said chain. When using my machine in a running stream I use only the 100 blades 9 of the lower reach of the chain and so adjust the frames C as to bring said blades 9 in contact with the flowing water. And I may use any desired length of chain by providing supporting means.

I thus provide a new and novel machine adapted for use at either place which is compact, adjustable as to the pitch or lay of the land where used and adjustable by new and novel means as to the relative leads 110

of the blade carrying chain belt without changing the length of said chain or using belt tighteners.

Having thus described my invention and 5 its operation I desire to secure by Letters Patent and claim:—

1. In a wave motor the combination of a rigidly mounted frame; of vertical angle iron supports thereon; other frames vertically adjustable as to said supports; a chain belt operable over sprocket wheels which are mounted in said last mentioned frames and other sprocket wheels pivoted to said angle iron supports, and means to raise and 10 lower the first mentioned sprocket wheels to adjust the distance between the leads of said chain belt.

15 2. In a wave motor the combination of a

rigidly mounted frame; of vertical angle iron supports thereon; other frames vertically adjustable as to said supports; a chain belt operable over sprocket wheels which are mounted in said last mentioned frames and other sprocket wheels pivoted to said angle iron supports, and means to raise and 20 lower the first mentioned sprocket wheels to adjust the distance between the leads of said chain belt; said means consisting of braces on which said first mentioned sprocket wheels are mounted; a pinion and 25 a rack mounted on the last mentioned frames and the rack connected with said braces by 30 U-shaped pieces.

In testimony whereof I have affixed my signature.

CHARLES H. ROBERTS.
